UNITED STATES PATENT OFFICE.

FLORA E. THOMAS, OF MELROSE, MASSACHUSETTS.

DESIGN FOR A CURTAIN HOLDBACK.

Application filed July 28, 1926. Serial No. 18,521. Term of patent 3½ years.

To all whom it may concern:

Be it known that I, FLORA E. THOMAS, a citizen of the United States, residing at Melrose, in the county of Middlesex and State of Massachusetts, have invented a new, original, and ornamental Design for Curtain Holdbacks, of which the following is a specification, reference being had to the accompanying drawing, forming part thereof.

The figure is a view in perspective of a curtain holdback, showing my new design.

I claim:

The ornamental design for a curtain holdback, as shown.

FLORA E. THOMAS.
